PROCESS FOR THE CONTINUOUS PREPARA-
TION OF ACETIC ACID FROM ACETALDE-
HYDE

Karl Wiesler, Constance, Germany, assignor, by
mesne assignments, to the firm of Deutsche
Gold- und Silber-Scheideanstalt vormals
Roessler, Frankfort-on-the-Main, Germany, a
corporation of Germany

Application February 14, 1930, Serial No. 428,456
In Germany February 27, 1929

7 Claims. (Cl. 260—116)

It is known that in the oxidation of acetaldehyde with oxygen labile intermediate products (peracid) are formed which can give rise to explosions. For obviating the difficulties resulting from this it has been proposed amongst other things, to add catalysts, for example manganese salts, for the purpose of destroying the peracid. Another proposal concerns the destruction of the peracid by heat, whereby during the given delay periods temperatures of about 100° C. are necessary in commercial apparatus. The destruction of the peracid by such methods has the effect of a corresponding loss of initial substance as the peracid thereby decomposes with the development of carbon monoxide and carbon dioxide and small quantities of methane. Finally, such methods have the further disadvantage that the heat developed by the reaction, which moreover renders extensive cooling methods necessary, is further considerably increased.

According to the present invention a continuous production of acetic acid from acetaldehyde is effected in a non-dangerous manner, in that the peracetic acid formed is maintained in great dilution by continuous circulation of crude acetic acid, for example, in concentrations of less than 0.2% and in this form having a large surface, is caused to react with gaseous acetaldehyde.

It has been shown to be possible to withdraw the peracid formed with further quantities of aldehyde so as to obtain a successful practical conversion free from loss without the peracid concentrations being able to increase in an appreciable manner at any single place of the apparatus.

Therefore, in working according to the invention it is possible to omit the use of catalysts or heat for the purpose of destroying all other unavoidable peracids as in the hitherto usual methods.

The conversion of the peracid with the acetaldehyde is effected according to the equation

or

In this way no loss of aldehyde occurs, also no oxygen is used for side reactions which have the effect of a deleterious increase of the reaction heat.

When carrying out the invention, crude acid poor in peracid is continuously circulated at a certain rate. This crude acid is mixed in a cer-

tain proportion with the acetic acid containing peracid which is freshly formed by the oxidation of acetaldehyde with air. The peracid concentration of the mixture is thereby reduced to the desired low value, which is non-injurious, for example to 0.2% or less. This diluted solution of peracetic acid in crude acetic acid continues the circulation and is now caused to react with gaseous aldehyde on a large surface, preferably at relatively low temperatures, for example such between 20 and 50° C. The peracid reacts with acetaldehyde while forming acetic acid. The peracid concentration in the circulating crude acid is thereby reduced to such an extent that the produced crude acid poor in peracid on repeating the circulation can again be used for diluting freshly formed acetic acid containing peracid. In this manner, the peracid is kept in such dilution in all parts of the apparatus and also where it is preferably formed that it can never occur in quantities which could exert any detrimental effect. In this manner, the reaction takes place between peracid and acetaldehyde, as has been found, almost exclusively according to the above equations.

The conversion of the peracid into acetic acid can, for example, be effected in towers provided with cooling devices and filled with suitable filling material. With suitable regulation of the reaction temperature it is easily possible to reduce peracid by the action of aldehyde to quite small, no longer injurious quantities, for example, a few hundredths per cent, with the formation of acetic acid, so that the now practically peracid-free crude acid is available for diluting the reaction mixture at other parts of the apparatus. As has been found, it is also possible to carry out the destruction of the peracid in the manner described if the aldehyde vapours are mixed with oxygen-containing gases, whereby the incidental formation of fresh quantities of peracid can still be effected. In any case the oxygen content of such gases should no longer be too great, it should, for example, not be more than about 10% of the aldehyde-containing gas mixture.

In carrying out the invention the operation can be carried out for example in such a manner that the initial substances, namely liquid acetaldehyde and oxygen, or oxygen containing gases, for example air, are introduced into a vessel which is provided with a good acting stirring mechanism and a cooling device, and is connected with one or more towers which are filled with suitable filling material, for example Raschig rings and are also provided with cooling devices.

The vessel temperature is preferably kept below 70° C., for example from 60 to 70° C.

The crude acid continuously flowing out from the vessel is cooled in a cooler to, for example, 5 15° C. and pumped up into the towers, whilst the vapour mixture issuing from the vessel which contains the unconverted aldehyde, moderate quantities of oxygen and very small quantities of carbon dioxide enter into the tower from below, 10 so that the crude acid meets the aldehyde-containing gas mixture over a large surface. The temperature of the tower is kept, for example, between about 20 and 40° C. Temperatures of, for example, 40 to 50° C. only must occur in the 15 lowermost part of the tower, as otherwise a too vigorous after reaction is liable to occur there, between the undecomposed aldehyde and the oxygen still present, and therefore the runnings-off from the tower might show a higher peracid content than was desirable. The runnings-off from the tower consisting of crude acid which only contains a few hundredths percent of peracid, 20 is led back again into the stirring vessel and here now serves to reduce the peracid content in the vessel itself to a suitably small degree.

The invention also offers the advantage amongst others that the reaction temperature in the vessel can be kept comparatively low if only the stirring mechanism provides for a sufficiently 30 thorough mixing of the initial substances. Whereas in other processes for the oxidation of acetaldehyde with the use of pure oxygen as oxidizing agent, in general temperatures of 70 to 100° C. are required, for the present process 35 even with the use of oxygen-nitrogen mixtures, as for example air, thus under unfavourable conditions vessel temperatures of for example, 60 to 70° C. have proved to be suitable and quite sufficient.

40 At such lower temperatures the side reactions already above referred to a number of times involving losses and damage by development of heat occur in a relatively small degree. Lower temperatures favour the formation of peracid. 45 In the present case the peracid formed however, owing to the strong dilution on the one hand and the moderate temperatures on the other hand is converted in a large degree with the entering aldehyde to acetic acid, whilst the damage, for 50 example by heat, goes entirely to the background. The favourable course of reaction in the vessel is amongst others obvious, from the circumstance that in spite of the dilution with the continually circulating crude acid and the strong reduction 55 of the aldehyde concentration to, for example, only 1 to 1 1/2%, occasioned thereby very satisfactory procedures with excellent yields are obtained, owing to the elimination of undesired side reactions.

60 With the use of a plurality of the described towers which serve for the conversion of the peracid, the arrangement can be carried out in various ways. It has been shown to be preferable to pass the gases, issuing from the oxidation 65 vessel, through two of the said towers in succession. Each of these towers is sprayed with crude acid and the acid flows out of each tower directly into the oxidation vessel back again. In both towers, the reaction between peracid and acet- 70 aldehyde takes place on a large surface but the second tower acts in part as a washer for the waste gases, a part of the acetaldehyde unchanged in the gases being absorbed by the crude acid and returned to the oxidation vessel. The apparatus is then supplemented by a further washing

device, preferably in the form of a third tower, in which the acetaldehyde contained in the gases is recovered in known manner.

This tower is preferably sprinkled with acetic acid whose washing action is better than that 80 of water. Likewise, the recovery of the acetaldehyde is favourably effected by distillation of this washing agent.

It has already been proposed to use so-called reaction towers for the oxidation of acetaldehyde, eventually also with the separate method that the filling material of said towers, is previously moistened with acetic acid. The advantages of the present invention cannot be obtained with such methods of operation. If the passage 85 of large quantities of acetic acid ceases, the dilution of the peracid to the degree necessary for safety is not possible. Furthermore a favourable running conversion with further aldehyde, with practical avoidance of loss in the form of carbon dioxide, can only be obtained with sufficiently diluted peracid as is obtained according to the 90 present invention. A favourable method of operation according to the present process arises amongst others from the fact that the carbon dioxide content in the waste gases does not further increase during the passage of the latter 95 through the towers.

It has also been proposed to use towers with 100 fillings which only leave a small space for the passage of the gases. This method is directly dangerous as, with narrow interstices it is unavoidable that at small variations of pressure 105 stoppages will occur which reduce the flow of the acid or may temporarily hold it up entirely, so 110 that the peracid concentration may assume an appreciable value locally.

Furthermore, the strong flow of acid through 115 the tower as occurs according to the present invention has the further advantage that the regulation of the reaction temperature, which is of considerable importance for the efficient conversion of the peracid, is effected uniformly and reliably.

Examples

1. The vessel in which the reaction takes place is provided with an inlet member for acetaldehyde, and for air or oxygen and also with a cooling device and a mixing device. 45 kg. of acetaldehyde and 100 cubic meters of air are introduced continuously per hour. The temperature in the reaction vessel amounts to 65° C. The gas and acetaldehyde vapors which pass out are conducted into two towers arranged one behind the other, and filled with Raschig rings, both of these towers being each sprayed with the cooled crude acetic acid circulated at the rate of 250 kg. per hour. After the peracid contained therein has commenced to react with the rising acetaldehyde vapors at room temperature the acetic acid almost entirely free from peracid flows into the oxidation vessel. The acid flowing from the oxidation vessel contains 0.15% peracid which has been formed during the oxidation. Unaltered aldehyde is washed from the waste gases. The yield amounts to 96% of the theoretical amount. The oxidation can be continued for any suitable length of time and takes place entirely uniformly and continuously.

2. In regard to this reference is made to the diagrammatic illustration. In this A is the actual reaction vessel in which air and acetaldehyde form acetic acid. The full lines indicate the circulation of the liquid acid whilst the broken lines

indicate the path of the gases, and the chain dotted lines the path of the acetaldehyde. From the reaction vessel A the gases pass successively through the towers I, II, III and IV, in which they are freed from the unaltered acetaldehyde. There then follows the washing device VI in which the acetic acid is washed. The acetic acid itself circulates through the reaction vessel A, the cooler and the receiving vessel 6 the supply vessel 1 and the towers I and II, said reaction vessel A being provided with a water cooling coil 10. A portion, corresponding with the freshly formed acetic acid, passes from the supply vessel 1 to the supply vessel 3 and from this into the column V in which it is freed from acetaldehyde. The acetaldehyde itself is again returned to the reaction vessel A whilst the acetic acid free from acetaldehyde flows into the receiving vessel 5. From here a suitable portion is withdrawn as the finished product, whilst another portion passes to the supply vessel 2 and from here into the towers III and IV. The acetaldehyde-containing acetic acid obtained in these towers is again passed through the receiving vessel 4 back into the vessel 3 and from here passes for distillation of the acetaldehyde into the column V.

45 kilograms of acetaldehyde are oxidized at 45° C. per hour and by means of 100 cubic meters of air per hour. The crude acetic acid produced is circulated for spraying the towers and in the first tower at a rate of flow of 80 kilograms per hour and in the second tower at a rate of flow of 270 kilograms per hour. Thereupon 300 kilograms of crude acetic acid are circulated per hour through a distillation apparatus and thereupon freed from the dissolved acetaldehyde which is recovered in concentrated form, and then used for spraying two further towers with acetic acid freed from acetaldehyde, each at the rate of 150 kg. per hour.

The gases and vapours leaving the oxidation vessel pass in series through the four towers. The acetic acid flowing from the first two towers is returned into the oxidation vessel. The acetic acid passed through the next two towers is freed continuously from acetaldehyde in a distillation column, and from the pure acetic acid thus obtained a suitable portion is withdrawn as final product. The gas leaving the last tower is free from acetaldehyde vapours. In a further tower VI the waste gases leaving the fourth tower are washed with dilute liquids, for example water, for the recovery of the acetic acid contained therein. The acetic acid flowing from the oxidation vessel contains 0.1% peracid. The yield amounts to 97% of the theoretical amount. The oxidation can be carried out for any suitable

length of time and takes place entirely uniformly and continuously.

I claim:—

1. A process for the continuous production of acetic acid by the oxidation of acetaldehyde in liquid phase by means of oxygen, consisting in keeping in great dilution the peracetic acid contained in crude acetic acid and formed by the reaction, by continuously circulating crude acetic acid and causing the reaction of the solution of peracetic acid in the circulating crude acetic acid issuing from the oxidation process, said reaction taking place over a large surface with vaporous acetaldehyde from said oxidation process, the temperature during the reaction being below 50° C. 90

2. A process according to claim 1 in which the concentration of peracetic acid in the circulating crude acetic acid is kept below 0.2%. 85

3. A process according to claim 1 in which the circulating crude acetic acid amounts to a multiple of acetic acid produced by oxidation in unit time. 95

4. A process according to claim 1 wherein acetic acid containing small quantities of peracid is used as the circulating crude acetic acid. 100

5. A process for the continuous production of acetic acid consisting in bringing acetaldehyde in liquid phase into reaction with oxygen in a vessel, bringing the cooled, crude acid issuing from the reaction vessel into reaction over a large surface with the acetaldehyde-containing gas mixture issuing from the reaction vessel and returning a portion of said crude acid substantially freed from peracid to the reaction vessel. 105

6. A process for the production of acetic acid, 110 consisting in bringing acetaldehyde in liquid phase into reaction with oxygen by a thorough mixing in a vessel, cooling the crude acid containing peracetic acid issuing from the vessel, bringing said peracetic acid into reaction with the acetaldehyde-containing gases issuing from the reaction vessel in a tower at a temperature below 50° C., and partly returning into the mixing vessel the crude acetic acid thus obtained and substantially freed from peracid. 115

7. A process for the production of acetic acid, 120 consisting in bringing acetaldehyde in liquid phase into reaction with oxygen in a mixing vessel by a thorough mixing at temperatures between 60° and 70° C., cooling the crude acid containing peracetic acid issuing from said vessel, bringing said peracetic acid into reaction over a large surface with the acetaldehyde-containing gas mixture issuing from said vessel at a temperature below 50° C., and returning into said vessel the crude acetic acid thus substantially freed from peracid. 125
